UNITED STATES PATENT OFFICE.

FREDRICK ALFRED EDWARD JENKINS, OF SYDNEY, NEW SOUTH WALES, AUSTRALIA.

STYLUS BAR FOR TALKING MACHINES.

Application filed March 27, 1924. Serial No. 702,467.

To all whom it may concern:

Be it known that FREDRICK ALFRED EDWARD JENKINS, a subject of the King of Great Britain and Ireland, residing at 5 Haig Avenue, Summer Hill, Sydney, in the State of New South Wales, Commonwealth of Australia, engineer, has invented certain new and useful Improvements in Stylus Bars for Talking Machines, of which the 10 following is a specification.

This invention relates to the method of mounting stylus bars on the sound boxes of talking machines and has for its object an improved means of attaching the stylus bar 15 to the sound box whereby the stylus bar is permitted to oscillate freely and convey the vibrations imparted to it by the record to the diaphragm with as little resistance as possible.

20 The invention consists in mounting the stylus bar on three pin points one of which opposes the other two, the three points being in alignment with each other and in the same plane and the line through the three 25 points parallel to the plane of the diaphragm. The invention further consists in making pin points adjustable so that any irregularities or imperfections in the stylus may be counteracted.

30 The invention will be fully explained with reference to the accompanying drawings in which:

Figure 1 is a perspective view of a sound box of the horizontal type showing the 35 method of attaching the stylus bar according to this invention.

Figure 2 is a similar view of part of a sound box of the vertical type.

Figure 3 is a perspective view of a sound 40 box showing an alternative method of carrying out the invention.

Figure 4 is an enlarged elevation of the alternative method shown in Figure 3, and

45 Figure 5 is a perspective view of a sound box showing a further alternative method of carrying out the invention.

Referring to Figure 1, the sound box 6 has attached to it in any convenient manner a bracket 7 having three projecting arms 8, 50 9 and 10; the outer arms 8 and 9 carry screws 11 and 12 having pin points 13 and 14 which bear against the surface of the cross arms 15 of the stylus bar 16.

55 A third point 17 attached to the stylus bar 16 bears against the projecting arm 10 and opposes the pin points 13 and 14. The points

13, 14 and 17 are in the same plane and in alignment with each other and the line through the points is parallel to the plane of the diaphragm, so that the arms 15 of the 60 stylus bar are permitted to oscillate freely and convey the vibrations imparted to the stylus or needle by the record, with a minimum resistance to the diaphragm of the sound box.

65 In the vertical type of sound box (see Figure 2) the point 17 is attached to the sound box 6 and the screws 11 and 12 project through small brackets 18 formed on the sound box. The stylus bar 16 bears against the three points 13, 14 and 17 which are in the same plane and in alignment with each other. The point 17 as before opposes the points 13 and 14 and the line through the points is parallel to the plane of the dia- 70 phragm.

75 In the alternative method shown in Figure 3 the point 17 is slidably contained within a sleeve 19 attached to the sound box and is pressed against the stylus bar by a spring 20 the pressure of which may be varied by the screw 21, the bearing points 13, 14 and 17 being as hereinbefore set out in the same plane and in alignment with each other. As shown in Figure 4 the line A A of the pin 80 points 13, 14 and 17 is parallel to the plane of the diaphragm.

85 In the modification shown in Figure 5 the point 17 and arm 10 are replaced by a knife edge 22 which bears at right angles on another knife edge 23 formed in the stylus bar 16. The edge 22 is integral with the plate 24 which is adjustably secured to the sound box 6 by means of the springs 25 which bear against the heads of the screws 26. The 90 bearing points 13, 14 and 17 are also in this case in the same plane and in alignment with each other.

95 In all cases the points 13 and 14 are mounted adjustably so that allowance may be made for irregularities in the construction of the stylus bar.

I claim:

1. In a talking machine in combination, a sound box having a diaphragm, a stylus bar, spaced arms carried by and projecting laterally from the sound box and arranged on opposite sides of the stylus bar, horizontal arms extending in opposite directions from the stylus bar and arranged in proximity to the arms of the sound box, pins mounted through the ends of one set of said

- arms and having pointed ends bearing against the adjacent arms of the other set, the axes of the pins being parallel with the axis of the stylus, a third intermediate bearing member arranged in alignment with the axis of the stylus and having a sharpened portion acting in opposition to the pointed ends of the pins whereby the arms of the stylus bar are permitted to oscillate freely
- 5 10 transversely and convey the vibrations imparted to the stylus with minimum resistance to the diaphragm, the pins being adjustable so as to counteract irregularities in the stylus bar, and the points of engagement 15 of said pins and bearing member being arranged in the same plane and in alignment with each other so that a line drawn through the points is parallel to the plane of the diaphragm of the sound box.
- 20 2. In a talking machine in combination, a sound box having a diaphragm, a stylus bar, spaced arms carried by the sound box and projecting laterally therefrom, the outer arms being arranged on opposite sides of 25 the stylus bar and in the same plane, the other arm being positioned between the
- outer arms in a different but parallel plane, opposed arms on the stylus bar arranged adjacent the outer arms on the sound box, pins adjustably arranged between the outer arms 30 and the arms on the stylus bar, another bearing member arranged in alignment with the longitudinal axis of the stylus and parallel with the axes of the pins and coacting with the stylus bar and the medial arm and 35 acting in opposition to the pins whereby the arms of the stylus bar are permitted to oscillate freely and convey the vibrations imparted to the stylus, with a minimum resistance, to the diaphragm, and the points of 40 engagement of the pins and bearing member being arranged in the same plane and in alignment with each other so that a line drawn through the points is parallel to the plane of the diaphragm of the sound box. 45
- In testimony whereof he has affixed his signature in presence of two witnesses.

FREDRICK ALFRED EDWARD JENKINS.
